(57) **CLAIM**

The ornamental design for a wireless router, as shown and described.

DESCRIPTION

FIG. 1 is a top, front and left side perspective view showing my new design for a wireless router,

FIG. 2 is a top left side perspective view thereof,

FIG. 3 is a top, rear and right side perspective view thereof,

FIG. 4 is a top and front perspective view thereof,

FIG. 5 is a bottom plan view thereof, and,

FIG. 6 is a bottom and rear perspective view thereof.

The broken lines shown throughout the views, which are immediately adjacent to the shaded areas and define unshaded regions, represent the bounds of the claimed design, while all other broken lines are directed to environment and are for illustrative purposes only; the broken lines form no part of the claimed design. The adjustable antenna has been shown rotated to alternate positions in FIGS. 5 and 6.
